Knowles Loom Works, Worcester, Mass., a cor-
poration of Massachusetts

Application April 29, 1940, Serial No. 332,204

14 Claims. (Cl. 139—116)

This invention relates to improvements in retainers for decorative cords used in the weaving of curtain material and it is the general object of the invention to provide improved means by which such a retainer can be called into action selectively with respect to the several weft threads used in weaving the curtain.

In the weaving of certain types of curtains the body of the curtain is made as an open mesh weave and at desired intervals relatively coarse colored weft yarns are introduced for their decorative effect. The weft thread for the ground weave runs to the selvages of the curtain, but the color effects of the large yarns do not ordinarily extend the full width of the curtain, and in order to prevent waste of these colored yarns it is customary to use pins or retainers spaced from the selvages inwardly toward the center of the fabric. These retainers are controlled to move down behind the color yarn on the backward stroke of the lay prior to picking in order to hold the threads and prevent them from twisting or bending the warp of the ground weave.

In automatic looms on which these curtains are woven a so-called color rod ordinarily extends from the drop box end of the loom across to the magazine end, replenishment being effected in a single shuttle box at that end of the lay opposite the shifting shuttle boxes. It is an important object of our present invention to provide control connections on the color rod which rocks in coordination with the shifting of the shuttle boxes to determine on which picks of the loom the retainers shall be operative. The color rod is already present in multi-color weft replenishing looms and we use it to control the retainer selectively.

It is a further object of our present invention to subject the retainer pin to a force tending to move it to inoperative position and to overpower this force by a control derived from the color rod so that the retainer can move to operative position when the colored weft is being woven.

As already suggested it is desirable when weaving certain patterns to provide for more than one decorative weft and it is a further object of our present invention to introduce between the retainer and its color rod control a form of mechanism which will permit the retainer to be in operative yarn holding position for as many positions of the shuttle boxes as correspond to the desired number of decorative yarns.

Retainer pins as heretofore constructed and controlled have frequently caused scoring or grooving of the race plate due to the fact that

the pin has moved to its operating position by a quick downward motion. This is likely to occur when the retainer pin is released suddenly immediately prior to picking by a control exercised directly by the shifting shuttle boxes. It is a further object of our present invention to release the retainer pin when the lay is near enough to its forward position to prevent immediate movement of the retainer to weft holding position. This result we attain by using the aforesaid color selector rod of the weft replenishing mechanism. The comparatively early arrival of the color rod to its selected position, a condition desirable for the replenishing features of the loom, permits release of the retainer and engagement of a part thereof with a finger or the like on the lay which acts during rearward motion of the lay to permit the retainer to move gradually to its operating position. Because of this gradual movement there is little or no tendency for the retainer finger to move beyond its correct position and the grooving of the race plate is avoided.

With these and other objects in view which will appear as the description proceeds, our invention resides in the combination and arrangement of parts hereinafter described and set forth.

In the accompanying drawings, wherein a convenient embodiment of our invention is set forth,

Fig. 1 is an end elevation of a portion of a loom having our invention applied thereto.

Fig. 2 is a plan view of the structure shown in Fig. 1 on a reduced scale,

Fig. 3 is a diagrammatic view showing the successive positions of part of the retainer controlling mechanism as the shifting boxes move to place the various weaving shuttles in active position,

Fig. 4 is a plan view on an enlarged scale showing certain parts illustrated at the right hand of Fig. 2,

Fig. 5 is a rear elevation looking in the direction of arrow 5, Fig. 4,

Fig. 6 is a vertical section on line 6—6 of Fig. 4 showing the two positions which are assumed by a part of the control mechanism for the retainer,

Fig. 7 is a vertical section on line 7—7 of Fig. 4 showing the retainer controlled so as to be in inoperative position,

Fig. 8 is a view similar to a portion of Fig. 7, but with the retainer shown in dotted position to cooperate with the decorative yarns and in

the front center position in full lines, the retainer being lifted out of controlling position with respect to the decorative yarns, and

Fig. 9 is a detailed vertical section on line 9-9 of Fig. 4.

Referring to the drawings, particularly Figs. 1 and 2, the loom frame 10 is provided with a lay 11 on which is mounted a gang of vertically reciprocating shuttle boxes 12, which in this instance cooperates with four shuttles being designated from top to bottom as S', S², S³ and S⁴. These shuttles become active in a rotation determined by pattern mechanism not shown but well understood, their period of shifting occurring when the lay is near its front center position, or the right of its back and forth swing as viewed in Fig. 1. This reciprocation of the lay may be effected by a connector 13 driven in the usual manner by the top or crank shaft not shown.

The gang of shuttle boxes is mounted at the upper end of a rod 15 the lower end of which is pivoted as at 16 to a link 17 having a yielding arm 18 normally held toward the link by a spring 19. The parts 17 and 18 define a pocket 20 to receive a pin 21 on a box lifting lever 22. The upper ends of the parts 17 and 18 are hinged as at 23 to permit relative separation so that the lever 22 can move vertically without breakage of parts should the gang of shuttle boxes be held against vertical motion, as by a misplaced shuttle.

The mechanism for shifting the gang of shuttle boxes vertically is designated generally at B and comprises front and back shafts 25 and 26, respectively, which are rocked by mechanism not shown but well understood. A cam disk 27 secured to front shaft 25 is connected to a link 28, while a cam disk 29 fastened to rear shaft 26 is connected to a link 30. Link 28 is connected as at 31 to an arm 32 pivoted as at 33 to the loom frame. The box lifting lever 22 is pivoted as at 34 to the arm 32 and is also pivoted as at 35 to the upper end of the rear link 30. A counterweight 36 may be used if desired to offset the weight of the boxes at the front end of the lever 22.

Disk 27 has high and low dwells 40 and 41, respectively, while the rear disk 29 has similar high and low dwells 42 and 43, respectively. A floating lever 45 has front and back shoes 46 and 47, respectively, which rest on the disks 27 and 29, respectively. Lever 45 is pivoted at 48 to an ascending link 49 pivoted at 50 to an arm 51 secured to a rocking color selector rod 52. The rod 52 oscillates in fixed bearings one of which is shown at 53 and normally extends across the loom to have connection with the color selector of a multi-color weft replenishing mechanism not shown. The pivot 48 is supported by an arm 55 pivoted at 56 to a fixed support and keeps the feet 46 and 47 properly placed with respect to the disks. A torsion spring 57 around rod 52 acts on a collar 58 fixed to the rod and urges the latter in such a direction as to keep the lever 45 yieldingly down. This spring also tends to move rod 107 forwardly.

The matter thus far described is well understood and comprises one of the types of box shifting mechanisms employed heretofore on cotton looms, and the disks 27 and 29 are similar to those which have been used on multi-color weft replenishing looms more particularly of the cotton type. The two vertical positions of each

of the links 28 and 30 make it possible to render any one of the four shuttles active, the relationship being as follows: when shuttle S' is to be active and the boxes are to be in their lowest position, link 28 will be down while link 30 will be up, thus placing high dwells 40 and 42 under lever 45 to move the latter to the high position shown at line a, Fig. 3; when shuttle S² is to be active both links 28 and 30 will be up, thereby placing low dwell 41 and high dwell 42 under lever 45 to cause the latter to assume the position shown in full lines at b, Fig. 3; when shuttle S³ is to be active both the links 28 and 30 will be down, thus placing high dwell 40 and low dwell 43 under lever 45 to give the latter the position indicated by line c, Fig. 3; and, when shuttle S⁴ is to be active link 28 will be up while link 30 will be down, thereby placing low dwells 41 and 43 under lever 45 to give the latter the position indicated by line d in Fig. 3. The pivot 48 on lever 45 is located to the left of the center of the lever, preferably at a point where a vertical line passing through the lines a, b, c and d of Fig. 3 will be cut into equal segments by them. The box motion may be substantially the same as that shown in Wyman Patent No. 411,752 and the disks may be similar to those shown in Ryon Patent No. 1,030,748.

From the description given it will be understood that the vertical motion of link 49 is controlled by the box shifting mechanism and its positions are coordinated with the positions of the gang of boxes, the relationship being such that when link 49 and arm 51 to which it is attached are in the positions corresponding respectively to lines a, b, c and d of Fig. 3, the active shuttles will be, respectively, S', S², S³ and S⁴. The highest shuttle in the shuttle box is active when lever 45 is in its highest position, while the lowest shuttle is active when lever 45 is in its lowest position, and there is a correspondence of positions for the intermediate shuttles and positions of lever 45.

The high and low dwells occupy a relatively large part of the periphery of the disks and are so placed with respect to the connections between the disks and their links as to complete vertical movement of lever 45 considerably in advance of the ending of the corresponding box shifting motion. The placing of lever 45 may, if desired, be effected while the lay is at or close to its front center position and prior to picking. The reason for this early setting of the lever 45 is to initiate release of a selected reserve bobbin in the magazine before the depleted shuttle is picked toward the magazine. This last feature is set forth in the Ryon Patent No. 1,030,748 and has been in common use for many years.

The lay comprises a beam 60 carrying a reed 61 the upper part of which is held by a hand rail 62. The shuttle race 63 is below the cloth C the rearmost pick F of which designates the fell of the cloth. Extending rearwardly from the fell are the warp threads W and W' which are shifted by any desired form of harness mechanism to provide successive sheds during loom operation.

The loom frame has a breast beam 65 on which is mounted a temple T having a rearwardly extending shank 66 to which is secured the pod carrier 67 through which the woven fabric passes. The temple includes in its construction a housing 68 held adjustably on the breast beam as illustrated in Fig. 4, and the housing includes a spring 69 which normally holds the temple rear-

wardly but permits forward yielding motion thereof should a misplaced shuttle be moved against the temple as the lay approaches front center. Included in the construction of the temple is a shelf 70 over which the woven cloth passes. The temple is of usual construction and operates in the ordinary manner to keep the cloth spread to its proper width at a point close to the fell. As shown in Fig. 4, the pod carrier extends inwardly from the selvage L. The temple of itself forms no part of my present invention but is set forth because of its close relationship to the retainer to be described in detail hereinafter.

In carrying our invention into effect we provide two retainers, one for each side of the cloth being woven, and two control mechanisms, one for each retainer. Since the retainers and their control mechanisms are the same, a detailed description of one of them will be given and it will be understood that the other retainer and its control will be similar to the parts specifically described. Near one end of the breast beam, the right end as set forth in Fig. 4, we secure a bearing 70 in which is journaled the outer end of a rocking rod 71. A collar 72 is held adjustably on rod 71 by a set screw 73 and has a longitudinal slot 74 in the upper face thereof. As shown in Fig. 7 this slot receives an end of a retainer wire designated generally at 75. This wire extends into the collar as at 76 and is held in position by a set screw 77. The wire then extends upwardly and is bent laterally as at 78 below the top of the slot 74, the part 78 thereby being held against angular motion with respect to the collar. The wire then extends outwardly and is bent up as at 80, being curved and bent back on itself to form an upwardly projecting arm 81 from the lower rear part of which extends the retainer pin proper designated at 82. The end of the retainer pin swings around rod 71 as an axis and is so located as to project downwardly in the dotted line position of Fig. 8 at a position slightly behind the fell of the cloth when the retainer pin is in operating position. The shelf 70 on the temple moves forwardly in a horizontal plane at the time of forward yielding of the temple along a path above the rod 71 and below the horizontal section 78 of the retainer wire. In this way provision is made for forward movement of the temple without damaging the retainer pin or its mountings.

As viewed in Fig. 4 the left end of rod 71 extends through a bearing 85 secured to the breast beam 65 and projects to the left of said bearing to be surrounded by a torsion spring 86 one end of which is held by the bearing 85 as at 87 and the other end of which is held by a collar 88 angularly and longitudinally adjusted on the rod 71 and held in position by a set screw 89. The effect of spring 86 is to turn rod 71 and the retainer pin in a right hand or clockwise direction as viewed in Fig. 7 from which it is to be understood that spring 86 yielding holds the retainer pin in the position shown in the dotted lines in Fig. 8 when decorative wefts are being woven and when permitted to do so by a control to be described.

The control mechanism for the rod 71 and therefore the retainer pin comprises a lever 90 having a hub 91 mounted for free rotation on the rod 71. An upwardly extending arm 92 lies behind and has engagement with a lug 93 projecting upwardly from a collar 94 adjustably held on rod 71 by set screw 95. A pin 96 on arm 92 holds the rear end of a relatively strong tension spring 97 the forward end of which is held by a pin 98 secured to the bearing 85. The spring 97 is strong

enough to overpower the spring 86 and unless controlled by parts to be described will hold the lug 93 to the left or full line position shown in Fig. 6, thereby keeping the retainer in raised inoperative position.

The lower end 100 of lever 90 cooperates with a cam 101 which has a high dwell 102 and a low dwell 103. This cam is secured adjustably by set screw 104 to a stub shaft 105 rotatable in the lower part of stand 85. Secured to shaft 105 is an arm 106 connected to a diagonal rod 107 extending rearwardly and downwardly as indicated in Fig. 1. The high and low dwells 102 and 103, respectively, of the cam 101 are connected together by a riser shoulder 110 which causes or permits movement of lever 90.

The rear end of rod 107 extends through a head 115 adjustably positioned relatively to the rod by nuts 116, and the head is pivoted as at 117 to an arm 118 fastened to the rocking rod 52 as at 120. By reason of these connections between the color rod 52 and the cam 101 the latter will be given four different angular positions, depending upon the position of the shuttle boxes. It is apparent therefore that, dependent upon the position of the cam 101 relative to its supporting shaft 105, the lever 90 will assume one of the two positions indicated in full and dotted lines in Fig. 6.

In describing the operation it may be assumed that the shuttles S' and S² carry two distinctive types of decorative weft while the lower shuttles S³ and S⁴ carry the weft for the ground weave. The retainer pin must cooperate with the weft of the two upper shuttles S' and S² but must not cooperate with the ground wefts. Under this condition the lever 90 and the setting of cam 101 on the shaft 105 will be such that the high dwell 102 will control lever 90 when the decorative weft is being woven by shuttles S' and S². This condition will prevail because lever 45, when in positions a or b of Fig. 3, will hold rod 107 rearwardly to locate cam dwell 102 under lever 90. Under this condition the parts will be as shown in Fig. 8, lever 90 having been rocked in a clockwise direction around the axis of the rod 71 to move arm 92 rearwardly against the action of spring 97, thereby permitting spring 86 to turn rod 71 and the retainer pin to the dotted line position of Fig. 8. Movement of the retainer is limited by engagement of lug 93 fast on rod 71 with arm 92. The time at which spring 86 is permitted to act is an important feature of our invention and is determined as will now be set forth.

The gang of shuttle boxes ordinarily starts its shifting during the latter part of a forward stroke of the lay and is not completed until the lay reaches top center, or the mid position of the ensuing backward stroke. Because of the requirements of the replenishing mechanism, as already described, the rod 52 is given its complete movements before the boxes have completed their shifting. The disks 27 and 29 are designed with this in view, and act to rock rod 52 to its final positions while the lay is in forward position. The retainer is therefore released and starts rearwardly while a stop 125 on the handrail is far enough forward to engage arm 81. This engagement prevents quick movement of the retainer to the dotted line position of Fig. 8 and the retainer turns gradually as the stop 125 moves rearwardly. The retainer therefore moves to operative position by a motion which is controlled by the backward stroke of the lay. The stop moves away from arm 81, however, before the lay reaches picking position,

and the retainer is therefore behind the thread extending from the selvage to the shuttle with decorative weft about to become active. When the shuttle is picked therefore a short time later in the rearward stroke of the lay its weft will be held by the retainer pin which will resist the lateral force exerted by the weft and thereby prevent misplacement of the warp threads.

In order to prevent damage to the reed and cloth and also the retainer pin it is necessary to move the pin out of the path of the reed on the following forward beat of the lay, and this is accomplished by means of the stop 125 which strikes arm 81 on the forward motion of the lay to rock the retainer from the dotted to the full line position of Fig. 8 to clear the reed. This forward motion of the retainer pin is against the action of spring 86 and can occur despite the fact that the high dwell 102 holds the lever 90 as shown in Fig. 8 because of the ability of lug 93 to move forwardly away from and out of engagement with arm 92. Arm 90 will be positioned by the high dwell as long as decorative weft is to be woven.

When the weaving of decorative weft is completed, there will be a control exercised by the pattern mechanism not shown resulting in movement of one or the other of shaft 25 or 26, causing a shift of lever 45 and a rocking of rod 52 to a position which will locate the low dwell 103 under the lever 90. This condition is accompanied by a resumption of control of rod 71 by the relatively strong spring 87 which acts through arm 92 to advance lug 93 and therefore rock the rod 71 to the position shown in Fig. 7, thereby returning the retainer to inoperative position. Under this last named condition rearward motion of the lay will not be accompanied by movement of the retainer finger to weft holding position.

Should it be desired to operate the loom with but one decorative weft the position of cam 101 can be changed relatively to the short shaft 105 by means of the set screw 104 so that a shifting of the shuttle boxes from a position in which shuttle S' is active to that in which shuttle S² is active will be accompanied by movement of the low dwell 103 under the lever 90. In a similar manner, should it be desired to have three decorative wefts, the cam 101 will be set to keep high dwell 102 under lever 90 while shuttles S', S² and S³ are active.

The time at which the retainer is free to move rearwardly during the sweep of the lay is independent of the number of shuttles which are laying decorative weft. If control of the retainer is to be exercised by both disks 27 and 29 they will turn simultaneously, whereas if the control is to be exercised by but one of these disks, the movement will be in the same period as that during which both disks would move simultaneously. For this reason the controller pin is released at the same point in the sweep of the lay regardless of the number of shuttles which are weaving decorative weft.

Reference to Fig. 2 shows that there is a retainer pin at each side of the loom, each pin being controlled by the color rod 52. When a period of decorative weft laying begins the proper shuttle at the left hand side of the loom as viewed in Fig. 2 will be rendered active and the weft thread extending from it to the cloth will be in front of the left retainer. As the latter moves down therefore it will be behind the decorative weft and as the shuttle enters the 75

shed along a path behind the retainer its weft will be caught and held by the left retainer. The shuttle arrives at the opposite or replenishing side of the loom and therefore ceases to exert further tension on the weft before the finger 125 acts to lift the retainer on the forward stroke of the lay.

On the next backward stroke of the lay the shuttle will be at the right hand side of the 10 loom with its thread extending to the adjacent selvage in front of the right retainer pin. As the shuttle is therefore picked away from the right side along a path behind the right retainer pin the latter will catch the decorative 15 weft for the purposes and with the effects previously described.

From the foregoing it will be seen that we have 20 provided a simple control for decorative weft retainers derived from selective mechanism forming part of the usual weft replenishing loom. It will also be seen that the condition of a weft replenishing loom which required rod 52 to assume a completed setting before the boxes are fully 25 shifted is also of advantage by insuring movement of the control arm 92 rearwardly in ample time to allow the retainer to reach the dotted line position of Fig. 8 before picking. It will also be seen that the control, while derived from cam 101 and lever 90, permits rod 71 to move against the action of spring 86 when stop 125 rocks the 30 retainer forward. It will further be seen that the early release of the retainer pin by the color rod 52 prior to complete shifting of the shuttle boxes and while the lay is still in a forward position permits the retainer to move rearwardly with a gradual movement controlled by the lay, with the result that the retainer has no tendency to override its proper position and mutilate the race plate. It will further be seen that the cam 101 35 can be given several angular settings with respect to the control mechanism so that the loom can operate with one or more decorative wefts each of which can be properly held by the retainers.

Having thus described our invention it will be seen that changes and modifications may be made therein by those skilled in the art without departing from the spirit and scope of the invention and we do not wish to be limited to the details herein disclosed, but what we claim is:

1. In a loom having a lay reciprocating between front and back center positions and having shuttle boxes which shift with respect to the lay during the latter part of a forward motion of the lay and the first part of the succeeding backward motion of the lay to place any selected one of a plurality of weaving shuttles controlled by the shuttle boxes in an active position, a control member movable to a plurality of control positions corresponding to the positions of the shuttle boxes relatively to the lay, means to complete movement of the member to a control position prior to completion of the corresponding box shifting movement of the shuttle boxes, a filling retainer to cooperate with the thread of at least one of the weaving shuttles when the latter is in active position, connections between the member and the retainer to control the latter and move said retainer to inactive position when certain of the weaving shuttles are active, and means under control of the member to move the retainer to active position when said one weaving shuttle is in active position.

2. In a loom having a lay reciprocating between front and back center positions and having

a gang of shuttle boxes shiftable relatively to the lay to place in active position any selected one of a plurality of weaving shuttles controlled by the gang of shuttle boxes, a filling cord retainer movable to active position to hold the weft of at least one of the weaving shuttles when the latter is active and said retainer movable to an inoperative position when certain other of the weaving shuttles are active, a control member for the retainer, means to cause the controller to move to different positions corresponding to the different positions of the gang of shuttle boxes relatively to the lay, said means causing the member to complete a movement thereof to a control position prior to the completion of the corresponding shifting movement of the gang of shuttle boxes and while the lay is in forward position, means controlled by the member when the latter is in certain control positions to hold the retainer in inoperative position, and means under control of the controller and operative when the member is in a position different from said certain positions to move the retainer to operative position.

3. In a loom having a lay reciprocating between front and back center positions and having a gang of shuttle boxes which shift relatively to the lay during the latter part of a forward motion of the lay and the first part of the succeeding backward motion of the lay to place any selected one of a plurality of weaving shuttles in active position, a weft cord retainer movable to operative position to hold the thread of at least one of the weaving shuttles when the latter is active and movable to inoperative position with respect to the weft threads of the other shuttles, a control member for the retainer movable to a plurality of control positions corresponding to the different positions of the shuttle boxes relatively to the lay, means controlled by the controller to move the retainer to inoperative position when said other of the weaving shuttles are active, yielding means normally restrained by the means and released by the latter when the controller moves to a position corresponding to said one shuttle to move the retainer toward operative position, and means on the lay to move the retainer against the reaction of the yielding means away from operative weft holding position as the lay moves to front center position.

4. In a loom having a lay reciprocating between front and back center positions and having a gang of shuttle boxes which move relatively to the lay during a shifting interval which starts during the latter part of a forward motion of the lay and ends during the succeeding backward movement of the lay before the latter reaches back center position to place any selected one of a plurality of weaving shuttles controlled by the shuttle boxes in active position, a cord retainer movable to operative position to hold the weft of at least one of the shuttles when the latter is active and movable to inoperative position with respect to the weft of the remainder of the shuttles when the latter are active, a controller for the retainer movable to a plurality of controlling positions corresponding to the positions of the shuttle boxes relatively to the lay, means to complete the movement of the member to any selected controlling position prior to the end of the corresponding box shifting period, connections between the controller and the retainer to move the latter to inoperative positions when said other of the weaving shuttles are active, and means controlled by the controller to move the

retainer to operative position when said one weaving shuttle is active prior to the end of the box shifting interval during which said one weaving shuttle moves toward active position, whereby the retainer is in operative position prior to the end of the box shifting period.

5. In a loom having a lay reciprocating between front and back center positions and having a gang of shuttle boxes which shift relatively to the lay during a period starting as the lay approaches a front center position and ending at a given point in the next succeeding backward stroke of the lay to place any selected one of a plurality of weaving shuttles in active position at the end of a box shifting period, a thread retainer movable to operative position to hold the thread of at least one of the weaving shuttles when the latter is active and movable to inoperative position with respect to the weft of the other weaving shuttles when they are active, a controller movable to a plurality of controlling positions corresponding to the relative positions of the shuttle boxes with respect to the lay, means to complete the movement of the controller to a controlling position while the lay is near the front center position thereof and prior to the end of the box shifting period, connections between the controller and the retainer to move the latter to inoperative position when said other of the weaving shuttles are active, yielding means to move the retainer toward operative position when the controller moves toward the controlling position corresponding to that position of the shuttle boxes which places said one shuttle in active position, and means on the lay to control movement of the retainer toward operative position, said yielding means moving the retainer to operative position gradually during backward motion of and under control of the lay.

6. In a loom having a lay reciprocating between front and back center positions and having a gang of shuttle boxes which shift relatively to the lay during a period starting during a forward stroke of the lay and ending during the following backward stroke of the lay to place any selected one of a plurality of weaving shuttles in active position, a member movable to a plurality of controlling positions, means to coordinate the movements of the controller with the shifting movements of the shuttle boxes and complete the movement of said member to controlling positions prior to the completion of the corresponding box shifting period, a thread retainer, normally acting means controlled by the member to hold the thread retainer in inoperative position with respect to the threads of certain of the weaving shuttles when the latter are active, an element moved by the member when the remainder of said shuttles is active to overpower the normally acting means, and yielding means thereupon effective to move the thread retainer toward operative holding position with respect to the weft of said remainder of weaving shuttles when the latter are to be in active position.

7. In a loom having a lay reciprocating between front and back center positions and having a plurality of shuttle boxes shifting relatively to the lay to place any selected one of a plurality of weaving shuttles in active position at the end of a shifting interval starting during a forward stroke of the lay and ending during the next succeeding backward stroke of the lay, a controller to assume a plurality of controlling positions corresponding to the positions of the shuttle boxes relatively to the lay, means to complete movement of the con-

troller to controlling position prior to the end of the corresponding box shifting interval, a thread retainer, a spring to hold the retainer inoperative with respect to the weft of certain of the weaving shuttles when the latter are active, connections from the controller to the spring to overpower the latter when the remainder of said weaving shuttles is active and the controller is in position corresponding to said remainder of the shuttles, and a second spring weaker than the first spring to be thereupon operative to move the retainer toward operative position to hold the weft of said active remainder of the weaving shuttles.

8. In a loom having a lay reciprocating between front and back center positions and having a plurality of shuttle boxes shifting relatively to the lay to place any selected one of a plurality of weaving shuttles in active position at the end of a shifting interval starting during a forward stroke of the lay and ending during the next succeeding backward stroke of the lay, a controller to assume a plurality of controlling positions corresponding to the positions of the shuttle boxes relatively to the lay, means to complete movement of the controller to any controlling position prior to the end of the corresponding shuttle box shifting interval, a thread retainer, a relatively strong spring normally holding the retainer inoperative with respect to the weft of certain of the weaving shuttles when the latter are active, connections from the controller to the spring to overpower the latter when the remainder of said weaving shuttles is active and the controller is in position corresponding to said active remainder of the shuttles, and a second spring weaker than the first spring thereupon operative to move the retainer toward operative position to hold the weft of said active remainder of the weaving shuttle, said connections including a cam connected to and moved by the controller and a lever movable by the cam and connected to the relatively strong spring.

9. In a loom having a lay reciprocating between front and back center positions and having a plurality of shifting shuttle boxes which shift relatively to the lay to place any selected one of a plurality of weaving shuttles in active position during a shifting period starting during a forward stroke of the lay and ending during the next succeeding backward stroke of the lay, a controller to assume a plurality of controlling positions corresponding to the positions of the shuttle boxes relatively to the lay, means to give the controller a complete movement to any selected controlling position while the lay is near its front center position and prior to the end of the corresponding shuttle box shifting period, a thread retainer movable to operating position to hold the weft of at least one of the shuttles when the latter is active and movable to inoperative position out of holding position with respect to the weft of the other shuttles when the latter are active, a stop on the lay to control movement of the retainer to operating position, connections between the controller and the retainer including a part controlled by the controller to hold said retainer in inoperative position out of holding position with respect to the wefts of said other shuttles when the latter are active, said controller when moving to a controlling position corresponding to said one shuttle when the latter is active moving said part out of controlling relationship with respect to the retainer while the lay is near its front center position,

5 and means thereupon operative to move the retainer toward operating position under control of said stop on the lay, the stop acting during backward motion of the lay to enable the last named means to move the retainer gradually to operating position prior to the end of the corresponding box shifting period.

10. In a loom having a lay reciprocating between front and back center positions and having a plurality of shifting shuttle boxes which shift relatively to the lay to place any selected one of a plurality of weaving shuttles in active picking position at the end of a box shifting period starting during a forward stroke of the lay and ending during the next succeeding backward stroke of the lay, the loom having a weft cord retainer to be in operative position to hold the weft of at least one of the weaving shuttles when the latter is active and said retainer to be in inoperative position and ineffective to hold the wefts of the other of the weaving shuttles when the latter are active, and the loom having also a controller having movements coordinated with the shifting movements of the shuttle boxes relatively to the lay, the controller movable to controlling positions corresponding to the positions of the shuttle boxes relatively to the lay prior to the completion of the corresponding box shifting periods and while the lay is near front center position, that improvement comprising means controlled by the controller and effective when the latter is in the controlling positions corresponding to said other shuttles when the latter are active to hold the retainer in inoperative position, disabling means connected to the controller and the first named means to move the latter out of control position with respect to the retainer when said controller moves to the controlling position corresponding to said one shuttle when the latter is active and when the lay is near front center position, and moving means normally prevented from acting by the first means thereupon operative to move the retainer toward operative position.

11. In a loom having a lay reciprocating between front and back center positions and having a plurality of shifting shuttle boxes which shift relatively to the lay to place any selected one of a plurality of weaving shuttles in active picking position at the end of a shuttle box shifting period starting during a forward stroke of the lay and ending during the next succeeding backward stroke of the lay, the loom having a weft cord retainer to be in operative position to hold the weft of at least one of the weaving shuttles when the latter is active and said retainer to be in inoperative position and ineffective to hold the wefts of the other of the weaving shuttles when the latter are active, and the loom having also a controller having movements coordinated with the shifting movements of the shuttle boxes relatively to the lay, the member movable to controlling positions corresponding to the positions of the shuttle boxes relatively to the lay prior to the completion of the corresponding box shifting periods and while the lay is near front center position, that improvement comprising means controlled by the controller and effective when the latter is in the controlling positions corresponding to said other shuttles when the latter are active to hold the retainer in inoperative position, disabling means connected to the controller and the first named means to move the latter out of control position with respect to the retainer when said member

moves to the controlling position corresponding to said one shuttle when the latter is active and when the lay is near front center position, moving means normally prevented from acting by the first means thereupon operative to move the retainer toward operative position, and lay controlled means acting in conjunction with said moving means to move the retainer gradually to operative position during backward motion of the lay.

12. In a loom having a lay reciprocating between front and back center positions and having a plurality of shifting shuttle boxes which shift relatively to the lay to place any selected one of a plurality of weaving shuttles in active picking position at the end of a box shifting period starting during a forward stroke of the lay and ending during the next succeeding backward stroke of the lay, the loom having a weft cord retainer to be in operative position to hold the weft of at least one of the weaving shuttles when the latter is active and said retainer to be in inoperative position and ineffective to hold the wefts of the other of the weaving shuttles when the latter are active, and the loom having also a controller having movements coordinated with the shifting movements of the shuttle boxes relatively to the lay, the controller movable to controlling positions corresponding to the positions of the shuttle boxes relatively to the lay prior to the completion of the corresponding box shifting periods and while the lay is near front center position, that improvement comprising means controlled by the controller and effective when the latter is in the controlling positions corresponding to said other shuttles when the latter are active to hold the retainer in inoperative position, disabling means connected to the controller and the first named means to move the latter out of control position with respect to the retainer when said member moves to the controlling position corresponding to said one shuttle when the latter is active and when the lay is near front center position, and moving means normally prevented from acting by the first means thereupon operative to move the retainer toward operative position, said disabling means including a cam to actuate the disabling means, and said cam moved by the controller in timed relation therewith.

13. In a loom having a lay reciprocating between front and back center positions and having a plurality of shifting shuttle boxes which shift relatively to the lay to place any selected one of a plurality of weaving shuttles in active picking position at the end of a box shifting period starting during a forward stroke of the lay and ending during the next succeeding backward stroke of the lay, the loom having a weft cord retainer to be in operative position to hold the weft of at least one of the weaving shuttles when the latter is active and said retainer to be in inoperative position and ineffective to hold the wefts of the other of the weaving shuttles when the latter are active, and the loom having also a controller having movements coordinated with the shifting movements of the shuttle boxes relatively to the lay, the controller movable to controlling

positions corresponding to the positions of the shuttle boxes relatively to the lay prior to the completion of the corresponding box shifting periods and while the lay is near front center position, that improvement comprising a cam having high and low dwells connected to and movable by the controller to positions corresponding to the controlling positions of the controller, means controlled by the cam and operative when cooperating with one of said dwells to hold the retainer in inoperative positions when said other of the shuttles are active, said controller when moving to the position corresponding to said one shuttle when active moving the other dwell of the cam into controlling relationship with the means to move the latter away from control position with respect to the retainer, and moving means thereupon operative to move the retainer toward operative position to cooperate with the thread of said one active shuttle prior to completion of the corresponding shifting of the shuttle boxes.

14. In a loom having a lay reciprocating between front and back center positions and having a plurality of shifting shuttle boxes which shift relatively to the lay to place any selected one of a plurality of weaving shuttles in active picking position at the end of a box shifting period starting during a forward stroke of the lay and ending during the next succeeding backward stroke of the lay, the loom having a weft cord retainer to be in operative position to hold the weft of at least one of the weaving shuttles when the latter is active and be in inoperative position and ineffective to hold the wefts of the other of the weaving shuttles when the latter are active, and the loom having also a controller having movements coordinated with the shifting movements of the shuttle boxes relatively to the lay, the member movable to controlling positions corresponding to the positions of the shuttle boxes relatively to the lay prior to the completion of the corresponding shuttle box shifting periods and while the lay is near front center position, that improvement comprises a cam having high and low dwells connected to and movable by the controller to positions corresponding to the controlling positions of the controller, means cooperating with the cam and operative when cooperating with one of said dwells to hold the retainer in inoperative position when said other of the shuttles are active, said controller when moving to the controlling position corresponding to said one shuttle when active moving the other dwell of the cam into controlling relationship with respect to the means to move the latter away from control position with respect to the retainer, moving means thereupon operative to move the retainer toward operative position to cooperate with the thread of said one active shuttle, and adjusting means to vary the range of movement of the cam with respect to the first named means to vary the number of positions of said cam during which each of said dwells shall cooperate with the first named means.

ALBERT A. GORDON, 3RD.
ALBERT PALMER.
